UNITED STATES PATENT OFFICE.

JOHN WILLISON, OF DERBY, ENGLAND, ASSIGNOR TO THE NATIONAL MALLEABLE CASTINGS COMPANY, OF CLEVELAND, OHIO.

AUTOMATIC CAR-COUPING.

1,201,669.

Specification of Letters Patent.

Patented Oct. 17, 1916.

Application filed February 21, 1914, Serial No. 820,175. Renewed August 10, 1916. Serial No. 114,296.

To all whom it may concern:

Be it known that I, JOHN WILLISON, a subject of the King of Great Britain, residing in Derby, England, and whose post-office address is 123 Palmerston street, Derby, in the county of Derby, England, have invented certain new and useful Improvements in Automatic Car-Couplings, of which the following is a specification.

10 This invention consists in improvements or modifications in the car couplers described in the specification to my United States patent application No. 114,294, which are of the type wherein each vertically pivoted coupler head is free to move laterally but may be locked in coupled condition with another similar coupler head by means of a pair of gravity locking blocks mounted one in each coupler head in recesses provided 15 for the purpose, the blocks overlapping each other when in locking position and being adapted to slide on inclined surfaces so that they can be moved out of engagement with each other to permit the relative lateral 20 movements necessary for effecting the coupling and uncoupling operations.

I have already proposed, as explained in my co-pending applications Nos. 114,293, 114,294 and 114,295 to improve car couplers 30 of the above type, by providing them with means adapted not only to shift the locking block along its inclined surfaces into a retracted or unlocked position, but also to retain it there so that the coupler heads on two 35 vehicles can, during shunting operations, engage each other without becoming coupled together. I have also proposed in these specifications to provide such couplers with lock set devices by means of which a locking 40 block shifted into the retracted or unlocked position is automatically retained in that position as long as the associated coupler head is in engagement with a similar coupler head, even though the locking block 45 be released by the retracting device, but the locking block becomes free to return automatically to the forward or locked position as soon as the two heads move apart and become disengaged.

50 The present invention consists in an automatic lock set device which, though performing the same functions as those just referred to, has an improved form and manner of operation.

55 Compared with my former lock-set de-

vices the improved device possesses the following advantages:—It consists of a single member and is therefore cheaper to make than a device with a number of parts or members; it is contained almost entirely 60 within the coupler head and consequently is less liable to injury from weather and externally-applied blows; it is more positive in action in extreme relative vertical positions of two engaging coupler heads, that 65 is to say should the difference in level of two engaging coupler heads, through some cause or other, amount to even more than half the depth of a head the device will still perform its duty efficiently; by reason of the 70 part of the lock-set device that is operated by an opposing coupler head having a position corresponding with the mid-depth of its own coupler head or nearly so; and it retains the locking block later, that is for a longer 75 period in its lock-set position, while the two opposing couplers are separating from each other, which is due to the movement of the device, when swept out of engagement with or brushed aside by the locking block, being 80 in an obliquely forward transverse direction, so that the device follows the direction of movement of the guard arm face of the opposing coupler against which face the 85 end of the device bears. The return movement of the device into engagement with the locking block takes place in the reverse direction, that is in an obliquely rearward transverse direction, and is affected by the 90 inwardly extending nose of the guard arm face of the opposing coupler.

The invention will be described with reference to the accompanying drawings, which show a coupler of the kind referred to and more particularly described and illustrated 95 in my patent application No. 114,292 having the present invention applied.

In the drawings Figure 1 is a part elevation of a coupler head; Fig. 2 is a longitudinal section on line 2—2 and Fig. 3 is a 100 part plan of a coupler, part of an engaging coupler head being shown in broken lines and in positions that it successively assumes in passing into or out of engagement, Fig. 4 represents an elevation and plan of a 105 locking block, and Fig. 5 shows a plan, side and end views of a lock-set piece.

The parts of the coupler and head in the accompanying drawings which correspond in substantial degree to parts described and 110

illustrated in the above cited specifications, are denoted herein by corresponding reference letters. The locking block f , the parts k and l of the block retracting device in the 5 coupler shank b and the coupler head a with its guiding surfaces g^2 , g^3 are substantially the same as those referred to in those specifications, the interior recess in the coupler head being modified merely for the reception 10 of the improved lock-set piece which is herein denoted by the reference letter q . This lock-set piece comprises a body portion q' and an upwardly projecting head portion q^2 which serves for retaining the locking 15 block in the unlocked position as explained below. When assembled in the coupler head, the body q' of the lock-set piece is housed or mounted in a laterally and outwardly directed slotway or aperture g^6 in the wall 20 of the recess g in the head and in the manner to be capable of sliding to and fro therein, and in a direction that is obliquely across the coupler head, while the head portion q^2 is accommodated within a suitably formed 25 recess or sinking p formed in or on the said wall, with its face q^3 in parallel relation but normally out of contact with the adjacent side of the locking block f and a projection f^0 thereon. On the upper part of the head 30 q^2 is a forwardly projecting guide q^6 which is adapted to rest on a corresponding ledge p' adjacent to the recess p , and serves to support the lockset piece during its sliding movements. The face q^4 of the head portion 35 q^2 is beveled off to a convenient angle and in such a manner that if the piece q be mounted in the slotway g^6 the pressure be applied normally to the face q^4 , the resultant force on the piece q , due to this pressure 40 and the resistance of the opposite side wall of the slotway g^6 , will tend to force the piece q in a direction longitudinal of the slotway. The length of the body q' is such that its end q^5 normally projects beyond the outer 45 wall of the coupler head to a desired extent, while the head portion q^2 is out of contact with the locking block.

The locking block is provided not only with the slotted projecting rib f^6 which engages in known manner with the dependent part g^4 of the coupler head in order to guide the locking block in its forward and backward movements, but also with the projection f^0 which, while the block is being retracted, will under certain conditions described below, pass beneath the head q^2 and thereby lift the head portion q^2 and cause the lock-set piece to tilt or turn on the lower outer edge of its slotway g^6 and in a direction laterally of the coupler head. As soon as the projection f^0 passes rearwardly of or beyond the end of the head q^2 during a retracting operation, the head q^2 if it has been thus lifted will, under the action of gravity, 60 fall in front of the projection f^0 and thereby

serve to retain the block in the retracted position.

As the lock-set piece q is normally out of engagement or contact with the locking block this latter can accordingly be pushed 70 backward sliding on its guiding surfaces g^2 , g^3 and move forward again into the locked position, without hindrance from the lock-set piece. When however, pressure is applied to its end q^5 then the body q' will 75 be caused to slide inwardly within the slotway or bearing g^6 so that the head portion q^2 moves into contact, or nearly so, with the adjacent side of the locking block. If the locking block be in its locking down position 80 and the piece q be pushed back, then the heel of the body q' will assume a position in rear of the projection f^0 . If the locking block be now retracted into the unlocking position the projection f^0 , being suitably 85 shaped for the purpose, will pass below moving lengthwise of the head q^2 and thereby lifting the head q^2 as described above. As the head is lifted, the lock-set piece will tilt, turning on the lower outer edge of the slot- 90 way.

As stated above, the end q^5 of the body normally projects beyond the outer face of its coupler head, but when this coupler head engages another coupler head, inwardly projecting nose or face d^2 of the guard arm of the opposing coupler head will engage the end q^5 and as the two coupler heads pass into final interlocking engagement the end q^5 of the part q' will be pressed inwardly in 100 a rearwardly and obliquely transverse direction, so that the head q^2 comes into close proximity or contact with the side of the locking block, as explained above. If the locking block be now retracted from the 105 locking down position by the device provided for the purpose the projection f^0 thereon first lifts the head portion q^2 and then passes beyond it, whereupon the head q^2 by reason of its weight drops again and 110 in front of the projection f^0 . The locking block will be retained in the retracted position by the engagement of the projection with the head of the lock-set piece after the retracting device has itself been turned back 115 to the position corresponding to the locking down position of the locking block, and until such time as the two coupler heads move out of engagement and thereby leave the lock-set piece free to slide outwardly 120 again in its bearing g^6 which it will do by reason of the pressure applied to the end q^4 by the projection f^0 of the locking block as the block automatically returns to its locking position under the action of gravity. To 125 facilitate this brushing aside of the lock-set piece, the slope or bevel of the face f^{10} of the projection f^0 should correspond to that given to the face or end q^4 on the lock-set piece.

If the axis of the slotway g^6 be parallel with the face d^3 of the coupler head, then the sliding movements of the body portion of the lock-set piece in a coupler head will 5 be in directions corresponding with those in which the guard arm of an opposing coupler head is at the moment moving into or out of engagement with the first said coupler head and the end q^5 . The guide on the head of 10 the lock-set piece, in addition to supporting the lock-set piece during its sliding movement, serves to retain the piece within the head of the coupler. The head is sufficiently weighted to drop or move automatically into 15 a lockset position in front of the retracted locking block after it has been lifted or tilted by said block during the retracting operation.

Having thus described the nature of the 20 said invention and the best means I know of carrying the same into practical effect, I claim:—

1. A car coupler of the vertical plane type comprising a coupler head having a 25 cavity therein, a gravity actuated lock mounted in said cavity, a projection on the lock, a lock-setting device mounted on the coupler head adapted in one position to be moved into a supporting engagement with 30 the projection on the lock by contact with an opposing coupler head, and to be forced out of such engagement with the lock by the gravity actuated movement of the lock as the couplers draw apart.

35 2. A car coupler of the vertical plane type comprising a coupler head having a cavity therein, a gravity actuated lock mounted in said cavity, and a lock-setting device mounted in a recess in one jaw of the coupler head, 40 the said device being adapted to be driven into supporting engagement with the lock for lock-setting by contact with an opposing

coupler head and to be forced out of said engagement by movement of the lock.

3. A coupler of the vertical plane type 45 having in combination a coupler head, a gravity-actuated lock, and a lock-set device, said lock being adapted to overlap and abut against the lock of a similar coupler to hold said couplers in interlocked position, the 50 lock-set device comprising a member movably mounted on the coupler head and capable of assuming a supporting and a non-supporting position with the lock, said member being held in supporting position by contact 55 with a similar coupler and being adapted to be shifted to non-supporting position by movement of the lock.

4. A coupler of the vertical plane type having in combination, a coupler head, a 60 gravity-actuated lock, and a lock-set device, said head having projections adapted to interlock with corresponding projections on a similar coupler by a relative lateral movement between said couplers, said lock being 65 movable into overlapping engagement with a corresponding lock on a similar coupler to hold the couplers against relative lateral movement, and said lock-set device comprising a member having a floating bearing 70 on the coupler-head, and adapted to assume a supporting and a non-supporting relation with said lock, said member being held in its supporting relation by contact with an opposing coupler head and being forced out 75 of supporting relation by the gravity-actuated movement of the lock.

In testimony whereof I have signed my name to this specification in the presence of two subscribing witnesses.

JOHN WILLISON.
